CLAIM

The ornamental design for an injection device as shown and described.

DESCRIPTION

FIG. 1 is a perspective view of the injection device;
FIG. 2 is a front elevational view thereof;
FIG. 3 is a rear elevational view thereof;
FIG. 4 is a side elevational view as seen from the left hand side of FIG. 2;
FIG. 5 is a side elevational view as seen from the right hand side of FIG. 2;
FIG. 6 is a top plan view thereof;
FIG. 7 is a bottom plan view thereof; and,
FIG. 8 is a further perspective view thereof.
